UNITED STATES PATENT OFFICE.

WILLIAM L. WEBER, OF CHICAGO, ILLINOIS.

METHOD OF AND MEANS FOR POLISHING METAL SURFACES.

No Drawing.

Application filed February 23, 1927. Serial No. 170,411.

This invention pertains to a method of and means for finishing, and polishing the contact surfaces of commutators, collector rings and the like of electric motors, generators and so forth, after they have been trued up, although susceptible of use in polishing other metal articles including those made from copper and copper alloys wherever the results attained by the invention 5 may be obtained and desired. For the purpose of disclosing the invention reference will be made to what is at present considered a preferred means for and method of accomplishing the result and to a motor or generator 10 commutator for illustrating the method and the use of means for carrying out the process.

It is very desirable to provide a hard and highly polished running surface on commutators, collector rings and the like of a dynamo-electric machine so that the brushes riding on such surface will not wear it excessively while making good electrical contact. No matter how well polished and 20 otherwise perfect a commutating or collector ring surface may be, when the motor or the like is put in use, running, dust and dirt in time, will cause the brushes to wear into the surface and form grooves. Sometimes also, 25 sparking occurs and often pits the surface badly. No matter what the cause, a rough and uneven running contact surface of a dynamo-electric machine interferes with proper functioning of the machine and it becomes 30 necessary to overhaul it and to refinish the contact surfaces.

Refinishing such contact surfaces usually consists in grinding or machining the commutator or rings preferably while the dynamo-electric machine is operating under "running balance" although the armature or other part to which the commutator or rings may be attached may be mounted between centers on a lathe and the irregular surface 40 machined or ground down as desired. Whether the surface be ground or machined the cutting is first rough to expedite the job, but thereafter the surface is ground with abrasive (usually in block form) of increasing fineness until the surface is as smooth as can be obtained. But the surface is not yet completed for it must be polished since a smooth glossy surface is most desirable for 45 many reasons.

It has consequently become the practice to set the brushes down on the surface and

run the machine without load until the brushes have polished the surface by long continued rubbing thereon, although if careful attendance is given to the machine this 50 operation may be done while the machine is in service. The proper condition of the surface, that is, the time when it is completely polished, is usually denoted by a darkened, somewhat steel blue or chocolate brown 55 appearance of the surface and the operation requires a comparatively long time depending upon the area of the surface to be polished, the quality and character of the copper and other factors.

I have discovered that the finishing and polishing operations may be expedited and an apparently much harder and more lasting surface may be obtained by adding a quantity of sulphur to the abrasive used for the 70 last one of the last grinding operations. This results in immediately producing a very hard, smooth and highly polished surface exceedingly resistant to wear.

Preferably finely powdered sulphur from 80 a very small percentage, say one-half of one per cent to any reasonable high percentage, say sixty-five per cent, more or less, all by weight, is mixed with the abrasive mixture before the latter is prepared in brick or block 85 form, so that the sulphur is thoroughly disseminated through or dispersed with and among the abrasive particles. The mixture is then put into the shape or shapes desired and baked at such temperature as may be 90 necessary to bind the whole together in a hard coherent and substantially homogeneous mass. The resulting product is ready for use.

One way of preparing a grinding block or 95 stone of this character, and the way I now consider preferable, is to mix about 20% of sulphur with about 80% of fine abrasive particles and heat the mass to a point where the sulphur melts. While the mass remains plastic it is molded to the form and shape desired and allowed to cool. Resins and gums like shellac may be added to yield a hard and tough product and not only may the proportion of sulphur be varied but the 100 kinds and quantities of abrasive particles and gums also may be varied as required for manufacturing conditions and degrees of stone hardness.

As intimated above, the product is to be 110 used for a final finishing operation or operations and for such reason, and, depending

upon the degree of roughness or fineness of the preceding cut and other factors, the abrasive particles with which the sulphur is mixed are of suitably lesser size. The degree 5 of fineness of the abrasive must be determined in almost every case by the workman.

In carrying out the process the dynamo-electric machine is started and the preliminary trueing cuts are made. Thereafter the 10 finishing block of abrasive containing the sulphur is applied to the surface and held thereagainst until the whole surface takes on a steel-blue or darkened appearance at which time it should be found to be highly 15 burnished, exceedingly smooth and resistant to abrasive action or wear. This finishing or polishing is accomplished almost instantaneously and the step does not vary from the ordinary grinding with an abrasive block 20 so far as the mechanical action taken by the worker is concerned and may be done in any of the usual manners. It is a novel and interesting fact, however, that when sulphur is mixed with the abrasive, a coarser abrasive 25 grain may be used to produce a very smooth and highly polished surface than would ordinarily be used for a finishing cut or grinding of the surface to be polished, and as is not the case with the latter, no further 30 polishing or rubbing is necessary to produce the steel-blue or slightly iridescent surface.

I do not know definitely whether or not the sulphur in the abrasive enters into chemical combination with the copper or copper 35 alloy, although it may do so. It is my theory that the heat generated by friction of the abrasive block containing the sulphur causes some of the sulphur to combine chemically with the copper with the formation of 40 cupric sulphide (Cu. S.) which the commutator or other copper element nearly resembles in color and appearance after treating, or with other metals to form sulphur compounds therewith, since it is reasonable to 45 assume that some actions or re-actions may take place. At any rate and regardless of theory the effect is to so harden a surface of a copper, copper alloy or other metal article to which it is applied as to make it extremely 50 hard and resistant to abrasion as well as to impart to it a very high polish. For instance, after polishing a copper commutator in accordance with the invention as disclosed, I have attempted to recut the surface so 55 polished and finished with a very coarse abrasive stone the composition of which was mainly pure silicon carbide, but I found that unusual force and a very great length of time were required to break through the hard 60 finish previously made by the sulphur stone.

While I have disclosed the invention in one of its preferred forms it will be appreciated that many modifications and variations

may be made without departing from its spirit or the scope of the appended claims. 65

I claim:

1. The method of polishing and hardening the contact surface of a commutator which consists in causing the surface to be treated to travel at a high speed, and applying 70 against said traveling surface a composition of sulphur and an abrasive material under sufficient pressure and heat to polish said surface and cause the sulphur of said composition to unite with the metal of said surface 75 whereby a hardened exterior is formed on said surface.

2. The method of polishing and hardening the contact surface of a commutator which consists in rapidly rotating the commutator, 80 and causing the surface of a composition block, including an abradant and sulphur, to contact the traveling surface of said commutator with sufficient pressure to produce a sulphur compound deposit upon the surface 85 so treated.

3. The method of polishing and hardening the contact surface of a commutator which consists in rotating the commutator to be treated, and urging against the traveling 90 perimeter of said commutator with sufficient pressure to generate a substantial degree of heat, a surface of a composition block including sulphur and an abrasive material, whereby a hard composite coating is produced upon the perimeter of said commutator.

4. The method of polishing and hardening the cuprous contact surface of a commutator which consists in rapidly rotating the 100 commutator and subjecting the revolving surface thereof to the action of a relatively stationarily disposed block including an abrasive mixed with sulphur, whereby said surface so contacted is simultaneously polished and provided with a hard copper sulphur compound coat. 105

5. An abrasive block for polishing and oxidizing commutators comprising an intimate mixture of abrasive material and sulphur, shaped to form a coherent and substantially homogeneous block adapted to be held against the surface of a revolving commutator whereby said surface is simultaneously polished and a hard composite coating 115 produced thereon.

6. The steps in a method of polishing commutators, collector rings and other articles containing copper in predominant proportions comprising, subjecting the surface to 120 be polished to friction and simultaneously applying free sulphur thereto.

In witness of the foregoing I affix my signature.

WILLIAM L. WEBER.
